UNITED STATES PATENT OFFICE

EMERT J. LATTNER, OF CEDAR RAPIDS, IOWA

DESIGN FOR A BURNER

Application filed April 11, 1933. Serial No. 47,760. Term of patent 7 years.

To all whom it may concern:

Be it known that I, EMERT J. LATTNER, a citizen of the United States, residing at Cedar Rapids, in the county of Linn and State of Iowa, have invented a new, original, and ornamental Design for Burners, of which the following is a specification, reference being had to the accompanying drawings, forming part thereof.

Figure 1 is a plan view in perspective of a burner showing my new design.

Figure 2 is a side view in perspective of the burner shown in Figure 1, and

Figure 3 is a front quartering view in perspective of the burner shown in Figures 1 and 2.

I claim:

The ornamental design for a burner, as shown.

In witness whereof, I hereunto subscribe my name this 7th day of April, 1933.

EMERT J. LATTNER.
